CLAIM

We claim the ornamental design for a shade for a camera, as
shown and described.

DESCRIPTION

FIG. 1 is a front top-down perspective view of the shade for
a camera;

FIG. 2 is a front top-down perspective view of the shade for
a camera;

FIG. 3 is a front elevation view of the shade for a camera;
FIG. 4 is a right side elevation view of the shade for a
camera;

FIG. 5 is a bottom plan view of the shade for a camera;
FIG. 6 is a back elevation view of the shade for a camera;
FIG. 7 is a left side elevation view of the shade for a camera;
and,

FIG. 8 is a top plan view of the shade for a camera.

In FIG. 2, the long broken lines show unclaimed environment
in the form of a camera.

In FIGS. 3, 5 and 6, the short broken lines indicate portions
of the article which form no part of the claimed design.

1 Claim, 4 Drawing Sheets
